UNITED STATES PATENT OFFICE.

FRANK ROWNICK, OF IRON RIVER, MICHIGAN.

DESIGN FOR AN ILLUMINATING LENS.

Application filed May 24, 1923. Serial No. 6,270. Term of patent 14 years.

To all whom it may concern:

Be it known that I, FRANK ROWNICK, a citizen of Yugoslavia, residing at Iron River, in the county of Iron and State of Michigan, have invented a new, original, and ornamental Design for Illuminating Lens, of which the following is a specification, reference being had to the accompanying drawing, forming part thereof.

The figure is a perspective view of an illuminating lens, showing my new design.

I claim:

The ornamental design for an illuminating lens, as shown.

FRANK ROWNICK.
